UNITED STATES PATENT OFFICE.

FRANK G. FEELEY, OF CHICAGO, ILLINOIS, ASSIGNOR TO M. D. KNOWLTON COMPANY,
OF ROCHESTER, NEW YORK, A CORPORATION OF NEW YORK.

BLANK-FEEDING MECHANISM.

Original application filed June 30, 1925, Serial No. 40,571. Divided and this application filed November 2,
1926. Serial No. 145,804.

The invention relates to mechanism for feeding blanks, such as paper board and the like, to machines for operating on the blanks, as for example, box forming and staying machines as shown and described in applicant's co-pending application, Ser. No. 40,571, filed June 30, 1925, of which the present application is a division.

The invention is illustrated in the accompanying drawings, in which:

Fig. 1 is a side elevation of the feeding mechanism and a portion of the box making machine.

Fig. 2 is a front end elevation.

Fig. 2^a is a sectional elevation of a feed table operating and supporting mechanism.

Fig. 2^b is a similar view showing another section of this apparatus.

Fig. 3 is an enlarged sectional side elevation of the front part of the machine.

Fig. 3^a is a detail view of a lock-out device for the table feed actuating means.

Referring more particularly to Figs. 1 to 3, inclusive, 1 indicates the main frame of the machine, preferably made up of side and end castings, in which is journaled a transverse main shaft 2 driven by an electric motor 3, mounted within the main frame, the shaft of the motor being connected to main shaft 2 by a train of reducing gearing 4, 5, 6 and 7. Secured to the front end of the main frame are two skeletonized brackets 10, 10 connected at their front ends by a cross bar 11, which brackets serve as supports for the blank magazine, feed table and certain other accessories of the machine. Journaled in the brackets 10, 10 is a cross shaft 12 upon which are rigidly secured two rocker arms 13, 13 the outer ends of which are finished with a short gear segment 15 and a plain segmental surface 14, the gear segment meshing with a rack 21 on the under side of feed table 20 and the cylindrical surface 14 constituting a rocker bearing for the table, as indicated in Fig. 2^a.

Mounted upon studs 16 fixed to the forward portions of the brackets 10 are two rocker arms 17, 17 finished at their outer ends with segmental cylindrical surfaces 18 cooperating with the plain surface on the bottom of the table 20. The two sets of rocker arms 13 and 17 on opposite sides of the machine are each coupled by connecting rods 19. The table is thus constructed and arranged to reciprocate horizontally with no

sliding friction, the reciprocation being effected by the cooperating gear segments 15 and racks 21 and the cylindrical arcuate ends of the rocker arms support the table with a roller-like action, thereby reducing friction of the moving parts to a minimum.

The table 20 is preferably formed as a single casting provided with a ribbed upper surface and a central longitudinal slot or opening in which is located a stationary guide rail 21. Adjustably mounted on the table 20 is a feeder block 31, the rear transverse portion of which is divided into two lateral sections to receive hardened steel feeder lips 32, which are of different heights on the opposite feeding edges and are reversible in the block to present either the high or low feeding edge to the blanks, when feeding heavy or light weight blanks. Adjustably mounted on the stationary guide rail 21 is a vertical back stop 22, which, with the front member 27 vertically suspended between the brackets 10, 10, serves to confine the blanks endwise on the table and in the magazine. The front stop 27 carries a slide or gate 29 which is vertically adjustable by means of a set screw 30, so that the lower edge of the slide or gate may be raised or lowered with respect to the top of the table to permit the discharge of one blank at a time, the adjustment being necessary to accommodate blanks of varying thickness.

The magazine sides 23 are in the form of cast plates suspended from transverse rods 24, 24 (Fig. 2) secured in the upper portions of the brackets 10, 10, said plates being slidable on said rods transversely of the table to accommodate blanks of different widths, the adjustment of the sides being effected by means of a shaft 25 having threads of opposite pitch on its respective ends engaging lugs 25' on the plates 23, said shaft 25 being operated by a crank 26 secured to one end thereof. The magazine sides 23 do not extend down to the top of the table 20, as it is desirable to have the feeder block 31 as wide as possible, so as to engage a considerable extent of the edge of the blank which is being fed in order that the feeding motion may be straight and true. It is also desirable to have the magazine sides as long as possible to properly confine long blanks. Therefore, when blanks narrower than the feeder block 31 and shorter than the sides 23 are being

handled, the feeder block must move under the lower edges of the magazine sides. In order to confine the lower part of the blanks under such conditions, adjustable extension side pieces 34 are secured to the lower edges of the magazine sides 23.

Journalized in housings formed as rearward extensions of the brackets 10, 10 is a shaft 36 carrying a lower feed roll 35, which cooperates with an upper feed roll 39, mounted in bearings on the lower ends of vertical slide rods 40, supported in the extensions of brackets 10 on opposite sides of the machine, each of said rods being acted upon by a coil spring 41 tending to force the upper roll 39 toward the lower roll 35, and the rods being adjusted to separate the rolls by a space a little less than the thickness of the blanks being fed to prevent jumping of the upper roll 20 when the blank enters the rolls, said adjustment being effected by nuts 42. This mounting of the upper roll provides a fairly uniform and constant pressure on the blanks in spite of variation in thickness of the stock 25 and permits the rolls to separate by movement of the upper roll, if, by accident, two or more blanks are simultaneously fed from the magazine. The lower feed roll 35 is driven by a belt 37 from a pulley 38, which is 30 operated by suitable gearing from the main shaft 2, the driving pulley being preferably provided with a suitable belt tightener 38' to maintain a proper tension on the drive belt 37.

As indicated, the feed table 20 is reciprocated by the oscillation of the two sets of rocker arms 13 and 17. In order to effect the rearward motion of the table away from the feed rolls, a positive driving connection is 40 provided as follows: a cam 50, fast to main shaft 2, is engaged by a roller 52 pivoted to fork 51, which straddles the hub of the cam 50, said fork having adjustably secured thereto a connecting rod 53, the opposite end of 45 which is connected to a crank arm 54 secured to shaft 12 upon which the rocker arms 13 are fixed. It will be seen, therefore, that the cam 50 actuates connecting rod 53 in one direction only, namely, in its outward movement from shaft 2, this movement effecting the retraction of the table 20 as the rocker arms 13 and 17 are moved toward the left, as 50 shown in Fig. 3. The feeding movement of the table and the return of connecting rod 53 to its normal position is accomplished by 55 helical springs 56 connected to the under side of the table and to the brackets 10, 10. The advantages of employing the springs to effect the active or operative movement of the 60 feed table are that the feeding movements are uniform and may be effected with great rapidity, but will nevertheless be instantly suspended should the blank being fed meet with an obstruction sufficient to damage or 65 derange any of the parts of the apparatus,

since, under such conditions, the springs 56 will yield and the feeding motion of the table would be arrested immediately.

It is frequently necessary or desirable to stop the feeding action of the table while the machine is in motion and this operation is effected by means of a hold-out latch, which is so constructed and arranged as to be operable to engage or release the feeding apparatus when the table is at the rear extremity of its stroke, that is to say, when the cam roller 52 is on the highest part of the cam 50. The mechanism to effect this object comprises an extension 60 of crank arm 54, which has an arcuate end adapted to be engaged by a bolt 61 slidably mounted in a housing 62 on bracket 10, said bolt being actuated by springs 66 and 67 interposed between the bolt and an eccentric actuator 63 mounted on shaft 64 provided with an operating handle 65. By turning the handle in one direction, the bolt 61 is advanced to engage the arcuate end of arm 60 of crank arm 54, when the latter has been moved to its upper position to retract the table, the frictional engagement between the bolt and the arm 60 being sufficient to prevent the table being returned by the springs 56. The friction caused by the side thrust of arm 60 against bolt 61 is also greater than the force exerted by actuating the spring of the bolt, this making it impossible to withdraw the latch at the wrong time and cause damage which might result if the cam roller 52 was some distance away from its cam when release of the hold-out latch is effected. The handle 65 of the bolt may be operated in either direction, at any time, but the bolt 61 will not engage or disengage the arm 60 except when the cam roller 52 is on the high point of its cam and the table 20 is in its extreme retracted position.

While the blank feeding device has been shown as applied to a box making machine, it is to be understood that it is not limited to such specific use, but is applicable and adapted for the feeding of blanks in sheet form and various sizes to machines of any type adapted to receive and operate upon such blanks.

What I claim is:

1. A blank feeding mechanism comprising a main drive shaft, a reciprocatory feed table, rocker arms supporting said table, feed rolls adjacent the discharge end of said table, drive mechanism connecting the main shaft and the table for retracting the latter, and spring means for effecting the working stroke of said table.

2. A blank feeding mechanism comprising a main drive shaft, a reciprocatory feed table, rocker arms supporting said table, feed rolls adjacent the discharge end of said table, a cam connecting rod actuating said rocker arms to retract the table, and spring means for effecting the working stroke of the table.

3. A blank feeding mechanism comprising a main drive shaft, a reciprocating feed table, rocker arms having arcuate ends supporting said table, gear toothed engagement between two of said arms and the table, feed rolls adjacent the discharge end of said table, a cam connecting rod actuating said rocker arms to retract the table, and spring means for effecting the working stroke of the table.

4. A blank feeding mechanism comprising a main drive shaft, a reciprocating feed table, rocker arms supporting said table, feed rolls adjacent the discharge end of said table, two pairs of rocker arms having arcuate ends supporting said table, tie rods connecting the rocker arms on each side of the table, a crank arm on the shaft of the rear rocker arms, said crank arm having an extension, a spring actuated cam latch secured to the machine frame and cooperating with said extension to lock and unlock the table in retracted position, a cam on the main shaft, a connecting rod between the cam and rocker arm to retract the table, and springs connected to the table and the machine frame to move the table in its working stroke.

5. A blank feeding mechanism comprising a feed table, rocker arms supporting the feed table for horizontal reciprocation, positive means operated from the drive shaft of the machine for retracting the table, springs for effecting the working stroke of the table, and laterally adjustable side guides suspended above the table.

6. A blank feeding mechanism comprising a feed table, rocker arms supporting the feed table for horizontal reciprocation, positive means operated from the drive shaft of the machine for retracting the table, springs for

effecting the working stroke of the table, laterally adjustable side guides suspended above the table, an adjustable back stop in advance of the front of the table, and a forward stop having a vertically adjustable gate fixed above the table at the forward limit of its stroke.

7. In a blank feeding mechanism the combination of a reciprocating feed table, an adjustable blank stop secured in advance of said table, a feeder block adjustably mounted on the table, feeder lips having blank engaging edges of different heights on said block, and feed rolls adjacent the forward limit of movement of said table.

8. In a blank feeding mechanism the combination of a reciprocating feed table, an adjustable blank stop secured in advance of said table, a feeder block adjustably mounted on the table, side guides mounted above and adjustable transversely of the table, means for adjusting said guides for blanks of different widths, and feed rolls adjacent the forward limit of movement of said table.

9. In a blank feeding mechanism the combination of a reciprocating feed table, an adjustable blank stop secured in advance of said table, a feeder block adjustably mounted on the table, said guides mounted above and adjustable transversely of the table with their lower edges elevated to permit the passage of the feeder block thereunder, adjustable side pieces secured to the lower edges of said guides, means for adjusting said guides for blanks of different widths, and feed rolls adjacent the forward limit of movement of said table.

In testimony whereof I affix my signature.

FRANK G. FEELEY.
